UNITED STATES PATENT OFFICE.

WILLIAM KELSO, OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA.

CAR COUPLER.

Application filed February 5, 1926. Serial No. 86,166.

This invention relates to car couplers of the vertical plane type wherein the knuckle is normally restrained from uncoupling rotation by means of a gravity actuated lock.

The primary object of the invention is to produce a car coupler of strong and simple construction in which the parts efficiently and reliably perform their functions. More especially the improvement is directed to means for ensuring certainty of performance of the lock setting operation which results in supporting the lock in unlocked position permitting a subsequent uncoupling rotation of the knuckle.

A principal feature of the invention involves the combination of a coupler head, a knuckle rotatably mounted thereon, a lock for the knuckle, and a lifter for actuating the lock, the lifter being slidably connected to the lock and preferably constituting means for cooperating with the coupler head and lock to prevent the latter from accidentally moving to unlocked position, and the lock and lifter being formed with inclined faces which cooperate with each other to cause the lock when moved to unlocked position to shift so as to come into supporting engagement with the knuckle while the latter is in coupled relation.

Other features of the invention pertaining to advantageous relations and forms of parts will hereinafter appear and be pointed out in the claims.

In the drawings illustrating preferred embodiments of the invention,

Figure 1 is a view, partly in side elevation and partly in vertical section, of a coupler embodying the invention, the parts being in normal locked relation.

Figure 2 is a view, partly in plan and partly in horizontal section, of a portion of the mechanism shown in Fig. 1.

Figure 3 is a sectional view on the line 3—3, Fig. 2, the knuckle opener being shown in elevation.

Figure 4 is a detail view, partly in elevation and partly in vertical section, showing the position assumed by the parts when the lock lifter acts to arrest accidental movement of the lock toward unlocked position.

Figure 5 is a detail side elevational view of the lock for the knuckle.

Figure 6 is a detail view corresponding to Fig. 4 but illustrating the position assumed

by the parts at the beginning of the unlocking movement of the lock.

Figure 7 is a detail view partly in elevation and partly in vertical section showing the relative position of the parts when the lifter has raised the lock to lock set position.

Figure 8 is a detail view, partly in elevation and partly in vertical section, showing a modified form of the invention employing a top operating lifter for actuating the lock, the parts being illustrated in normal locked relation.

The coupler 1 carries a knuckle 2, which is pivotally connected to the head by a knuckle pin 3. In the embodiment of the invention illustrated in the drawings the stem or shank 4, forming a part of the coupler body, is integrally connected to the head 1.

The knuckle 2 is normally restrained from outward rotation by a gravity actuated lock 5 slidably mounted in the coupler head. The lock is preferably constructed so that it may be moved to unlocked position either by means of a bottom operating lock lifter 6 or by a top operating lock lifter 7, the latter construction being illustrated in Fig. 8. In both forms of construction the lock and its lifter are so constructed as to be operatively connected with capability of relative sliding and tilting or pivotal movements. For this purpose it is preferred to provide the lifter, 6 or 7, as the case may be, with oppositely disposed trunnions 8 which operate in trunnion guideways or recesses 9 of the lock, the latter being fashioned with a rearwardly and upwardly opening slot for receiving the adjacent portion of the lifter. The upper ends of the trunnion guideways 9 extend to a point above and in advance of the center of gravity of the lock 5, thus enabling the lock to tilt or swing forwardly under the influence of gravity toward the tail of the knuckle when it is supported on the trunnions in raised or unlocked position. While, as will appear, other and more positive means are primarily designed to shift the lock so that it may be supported on the tail of the knuckle in lock set position, the relation of the lifter and lock by reason of which the latter may

tilt under the influence of gravity so as to assume lock set position, is advantageous in that it provides secondary means for ensuring the performance of a lock set operation.

should wear or injury render the means primarily serving that purpose incapable of performing their normal function. To permit the lock to tilt to lock set position after having been raised, the upper portion 11 of the rear face of the lock is cut away or inclined. For a similar purpose the front face of the lock toward the guard arm side of the coupler head is beveled as at 12.

10 The lock 5 is formed with a lug 13 which projects downwardly beyond the knuckle locking portion of the lock so as to form a lock set leg whose lower end is adapted to rest upon a lock set ledge or seat 14 formed 15 on the upper surface of the tail of the knuckle adjacent the lock. The lock set seat or ledge 14 extends only a part of the way along the rear upper edge of the tail of the knuckle and gradually diminishes or 20 tapers in width so that as the knuckle 2 opens the lock set lug 13 rides or is forced off the knuckle, thus permitting the lock to drop to a position in which the under surface of its knuckle locking portion is supported upon the upper surface of the knuckle tail. When the knuckle is subsequently rotated to closed position its tail is withdrawn from beneath the lock and the latter falls to locked position. The upper 25 portion of the lug 13 overlaps the inner end of the tail of the knuckle, as shown in Fig. 2, thereby functioning as a guide to prevent the lock from tilting forwardly until after it has been raised sufficiently to unlock 30 the knuckle. To guide the lock 5 when the latter performs an extended unlocking movement such as is required to actuate the knuckle opener, the coupler head 1 is formed with a vertically extending wall 15 which 35 cooperates with a projection 13 on the lock.

Below the trunnions 8 each of the forms of the lock lifter (6 and 7) is provided on its forward side with an inclined face or beveled shoulder 16 which is adapted to cooperate with a correspondingly inclined surface 17 at the bottom of the lifter receiving recess of the lock 5. These downwardly and forwardly inclined surfaces 16 and 17 are spaced from each other when the parts are in normal locked relation, as shown in Figs. 1 and 8. When, however, the lifter is actuated to move the lock 5 to unlocked position the initial unlocking movement of the lifter brings the inclined surface 16 of the latter into contact with the cooperating incline 17 of the lock, as shown in Fig. 6. Continued upward movement of the lifter, while the inclined face 17 of the lock is thus in contact with the corresponding inclined shoulder of the lifter, causes the lock to be raised to unlocked position permitting the knuckle to open. As soon as the lock has been raised sufficiently to unlock the knuckle it slides or gravitates downward and forward along the inclined surface 16 of the

lifter, tilting to lock set position, as shown in Fig. 7. In this position the lock set leg 13 rests upon the lock set seat 14 of the knuckle, thereby supporting the lock in elevated position. It will be appreciated that this construction renders the full weight of the lock 5 effective to cause it to move to its lock set position, thereby making the performance of this function more positive and speedy than would be the case if a mere overbalancing of the lock around a point of pivotal support were relied upon for that purpose. But, as heretofore explained, the locking block 5 and the trunnions 8 of the lifter are so related that the upper ends of the trunnion guides 9 of the lock are sufficiently above and in advance of the center of gravity of the lock to induce a forward swinging or tilting of the lock under the action of gravity, causing the lock to assume lock set position, thereby ensuring proper operation of the mechanism should the projection forming the inclined surface 16 of the lifter be broken off or worn to such an extent that it could not cooperate with the beveled surface 17 of the lock to shift the latter to lock set position.

It is preferred to construct each of the lock lifters 6 and 7 in a manner to provide means for preventing accidental unlocking of the lock resulting from shocks and jars of service. For this purpose both forms of lifter may be provided with a shoulder 18 which extends under a lock down shoulder 19 of the coupler head or body when the lock and its lifter are in locked relation. As shown in Fig. 4, if the lock 5 while in service should accidentally move toward unlocked position the lifter will be carried upwardly with it until the shoulder 18 comes into engagement with the lock down shoulder 19 of the coupled head, thereby arresting further unlocking movement of the lock 5. Efficient and positive functioning of the means for preventing accidental unlocking of the lock is enhanced by providing the lock lifter with a vertically extending face 20 which bears against the front face of the lock down shoulder or wall 19 when the parts are in locked relation; and the lifter is preferably provided on its forward side with a vertically extending face 21 which engages a corresponding face on the lock 5 when the coupler is locked. By cooperating with the coupler head and lock, respectively, these faces or shoulders 20 and 21 prevent the lifter from accidentally rotating in a direction which would cause its locking shoulder 18 to move from beneath the anti-creep shoulder or lug 19 of the coupler head.

For the purpose of rotating the knuckle to open position when the lock 5 is caused to execute an extended unlocking movement, the coupler is preferably provided with a

bell crank knuckle opener lever 22 which is pivotally mounted upon a horizontally extending pin 23 that may conveniently be cast in place in the head. The longer arm 5 of the knuckle opener extends downwardly behind the tail of the knuckle 2 so that when the knuckle opening lug 24 formed on the lock 5 engages the shorter arm the knuckle opener is rotated and the knuckle thereby forced to open position.

It will be perceived that my invention provides a car coupler in which the parts are strong and of simple form and in which highly efficient and reliable means are afforded for causing the lock to assume lock set position.

I claim:

1. A car coupler involving a coupler head, a knuckle rotatably mounted thereon, a lock 20 for the knuckle, and a lifter for actuating the lock, said lifter being slidably connected to the lock and having an inclined face for cooperating with the latter, said inclined face being adapted when the lifter executes an unlocking movement to move into engagement with the lock and cause the latter to move to unlocked position, the said lock after having been raised to unlocked position being adapted under the influence of 30 gravity to slide down the said inclined face and shift laterally so as to engage and be supported by said knuckle in a lock set position.

2. A car coupler involving a coupler head, 35 a knuckle rotatably mounted thereon, a lock for the knuckle, and a lifter for actuating said lock, the lifter and lock being slidably connected and one of them being provided with an inclined face for engaging the other, said inclined face constituting means for causing the lock to gravitate laterally toward and to engage and be supported by said knuckle in lock set position after the lifter has caused said lock to assume unlocked position.

3. A car coupler involving a coupler head, a knuckle rotatably mounted thereon, a lock for the knuckle and a lifter for actuating the lock, said lifter being slidably connected 50 to the lock and constituting means for preventing the latter from accidentally moving to unlocked position, and said lock and lifter being provided with cooperating inclined faces which are spaced from each other when the lock and lifter are in locked relation and which engage each other during movement of the lock to unlocked position, the said lock when raised to unlocked position being adapted to slide down the inclined face of 55 the lifter so as to shift laterally to assume lock set position.

4. A car coupler involving a coupler head, a knuckle rotatably mounted thereon, a lock for the knuckle, and a lifter for actuating the lock, said lifter being slidably connected 60

to the lock and being adapted to support the lock so as to permit it to tilt toward lock set position, and said lock and lifter being formed with inclined faces which are spaced from each other when the parts are in locked 70 relation and which cooperate with each other to cause the lock to shift toward lock set position after it has been moved to unlocked position by the lifter.

5. A car coupler involving a coupler head, 75 a knuckle rotatably mounted thereon, a lock for the knuckle, and a lifter for actuating the lock, said lifter being slidably and pivotally connected to the lock and constituting means for preventing the latter from moving accidentally to unlocked position, said lifter being provided with an inclined shoulder which is spaced from the lock when the lifter is in normal locked position and which engages the lock to impart an unlocking movement to the latter, the said lock being slidable down said inclined shoulder to lock set position.

6. A car coupler involving a coupler head, 80 a knuckle rotatably mounted thereon, a lock for the knuckle, and a lifter for actuating the lock, said lifter being slidably and pivotally connected to said lock and extending downwardly therefrom through an opening in the coupler head, said lock when moved to unlocked position by the lifter being adapted to swing toward and be supported by the knuckle while the latter is in closed position, and the lifter being provided with an inclined shoulder which is adapted to 100 move into engagement with the lock and down which the latter slides toward lock set position after having been moved to unlocked position.

7. A car coupler involving a coupler head, 105 a knuckle rotatably mounted thereon, a lock for the knuckle, and a lifter for actuating the lock, said lifter being slidably and pivotally connected to the lock and extending downwardly therefrom through an opening 110 in the coupler head and being adapted to cooperate with the lock and coupler head to prevent said lock from accidentally moving to unlocked position, said lifter being provided with an inclined face for engaging the 115 lock to cause the latter to tilt to a position enabling it to be supported by the knuckle while the latter is in closed position.

8. A car coupler involving a coupler head, 120 a knuckle rotatably mounted thereon, a lock for said knuckle, and a lifter for actuating the lock, said lifter being slidably and pivotally connected to the lock and being provided below its point of pivotal connection to the lock with an inclined face which is 125 adapted to move into engagement with the lock, said lock when moved to unlocked position by the lifter being adapted to slide along said inclined face so as to move to a position enabling it to be supported by the 130

knuckle while the latter is in closed position.

9. A car coupler involving a coupler head, a knuckle rotatably mounted thereon, a lock for the knuckle, a lock set seat on the knuckle for supporting the lock in unlocked position, and a lifter for actuating the lock, said lifter and lock having cooperating shoulders for preventing the lock from accidentally assuming unlocked position, and said lock and lifter being slidable with respect to each other and being provided with cooperating inclined faces which come into engagement when the lifter moves the lock to unlocked position, the said cooperating inclined faces constituting means for causing the lock under the influence of gravity to slide down the inclined face of the lifter so as to shift into engagement with said lock set seat and thereby be supported in unlocked position while the knuckle is closed.

10. A car coupler involving a coupler head, a knuckle rotatably mounted thereon, a lock for the knuckle, a lock set seat for supporting the lock in unlocked position, and a lifter for actuating the lock, said lifter being slidably connected to the lock and cooperating with the latter and with the coupler head to prevent the lock from accidentally moving to unlocked position, and said lock and lifter being provided with inclined faces which cooperate with each other to cause the lock to shift into engagement

with the said lock set seat while the knuckle is in closed position.

11. A car coupler involving a coupler head, a knuckle rotatably mounted thereon, a lock for the knuckle, and a lifter for actuating the lock, said lock being provided with a portion adapted to seat upon the tail of the knuckle to thereby maintain the lock in unlocked position while the knuckle is closed, said lifter being provided with trunnions forming means for slidably and rotatably connecting the lifter and lock, said lock being formed with guideways for said trunnions extending forward of the center of gravity of the lock, and said lifter being provided with an inclined face which is adapted to cooperate with the lock to cause the latter to shift under the influence of gravity so as to assume a position in which it is supported in unlocked position by the knuckle while the latter is closed.

12. A car coupler involving a coupler head, a knuckle, a lock for the knuckle, and a lifter for the lock, the lifter being provided with an inclined face and having trunnions and the lock having guideways for the trunnions, the inclined face on the lifter being adapted to engage the lock to lift the latter before the trunnions reach the ends of the guideways.

In testimony whereof I affix my signature.
WILLIAM KELSO.
